UNITED STATES PATENT OFFICE

2,500,508

PHYSICAL THERAPEUTIC TABLE

Peter Bachin, Chicago, Ill.

Refiled for abandoned application Serial No. 587,079½, April 7, 1945. This application June 25, 1946, Serial No. 679,130

2 Claims. (Cl. 128—24.1)

1

This instant application is a refile of my application Serial No. 587,079½, filed April 7, 1945, previously abandoned, and relates to improvements in physical therapeutic tables.

The main object of the invention is to provide a table of the class described for administering simultaneously or successively heat and mechanical vibration to a human body recumbent on said table and afflicted with chronic or acute diseases as arthritis, rheumatism, circulatory disturbances or suffering from excessive weight.

Another object is to provide an apparatus of the class described and of simple, enduring and economical construction and low operating cost.

These and other objects will become apparent as the following description is read in which the novelty of construction, combination and arrangement is set forth in detail. The description is amply illustrated in the accompanying drawings forming part of the application and wherein:

Figure 1 is a top plan view of the preferred embodiment of my invention.

Figure 2 is a side elevation.

Figure 3 is a longitudinal vertical section on line 3—3 of Figure 1.

Figure 4 is a bottom plan view of the table after the removal of the box and legs.

Figure 5 is a detail top plan view of the box.

Figure 6 is an elevation of the left hand (Figs. 1—3) end.

Figure 7 is an enlarged longitudinal vertical detail section on line 7—7 of Figure 5.

Figure 8 is an enlarged detail bottom plan view of the detail shown in Figure 7.

Figure 9 is an enlarged longitudinal vertical detail section on line 9—9 of Figure 1.

Figure 10 is an enlarged end view of the fan and motor.

Figure 11 is a wiring diagram of the electric circuits.

Figure 12 is a top plan view of a modified form of my invention.

Figure 13 is a top plan view of the box of the modification after removal of the rest for the patient.

Figure 14 is a vertical longitudinal central section on line 14—14 of Figure 12.

Figure 15 is a second modification.

Figure 16 is a wiring diagram of the same.

In the drawings, wherein like characters of reference designate like or similar parts throughout the several views, the invention is shown as embodied in a substantially rectangular table or support having near its corners four legs 5 each

2

provided at its lower end with a foot 6 resting on a suitable supporting surface (Figs. 2, 3, 6).

Between the upper end portions of the legs is arranged a box comprising a pair of parallel longitudinal boards 8 and a pair of parallel transverse boards 9, both standing on edge and supporting at their lower ends a bottom board 10 (Figs. 2, 3, 5). Each leg is provided at its upper end with an axial spring socket 12 opening through such end.

A plurality of spaced similar sockets are formed in each of the longitudinal box-boards and open through the upper edges thereof. Each socket provides a seat for the lower portion of a steel spring 14, the upper end of which is seated in one of a corresponding plurality of sockets 15 formed in a table top 18 having depending longitudinal and transverse walls 20 the lower ends of which are disposed slightly below the top surface of the legs and table box and exteriorly thereto (Figs. 3, 9). Angles 22 are attached by their upper horizontal legs and fasteners 23 to the lower face of the table top and also comprise vertical legs each provided at its lower end with a slot 25 in which a headed screw pin 26 slides. The inner end of the pin is embedded in or otherwise secured to the outer side of one of the transverse boards.

The table top supports a couch and is covered on its upper surface and sides with upholstery 28 held in place by a cover 30 of leather or other suitable material fastened by fasteners 31 to the lower edges of the depending walls 20 of the table top. The upholstery and cover are shaped to provide a foot rest 33 and head rest 34.

The table top, upholstery and cover are provided with five longitudinal slots 36 three of which are arranged in spaced relation adjacent the head rest while the other two extend from the foot rest (Fig. 1).

A bearing block 38 is attached by flanges extending from the upper ends of its sides and fasteners 39 to the under face of the table top and is connected at its lower side by similar fasteners to the laterally extending flanges of a cap 40. The cap and the bearing block provide a mounting for the housing frame of a motor M which has a shaft 42 carrying upon one end by means of a set screw 43 a fan 45. From the hub of the latter extend in diametrically opposite directions a pair of screws 47 on which weights 48 may be threaded (Figs. 3, 4). Figure 10 shows three weights on the right hand screw and one weight on the left hand screw to indicate the eccentric loading of the motor shaft.

The central part 50 of the box bottom 10 beneath the motor is slightly dished and provided with a pair of air openings 51. Similar openings are provided on opposite sides of the dished bottom portion (Fig. 3, 5). The central portions of the longitudinal box boards also have air openings 51 (Fig. 2, 5).

The dished part 50 and adjacent flat parts of the box bottom form the bottom of a chamber for the motor also bounded by a pair of vertical partitions 55 preferably of heat insulating material. These partitions are supported at their lower edges by the box bottom and each also separates the motor chamber from a heat chamber bounded by a partition 55 adjacent either transverse end of the table box (Fig. 5).

Each heat chamber communicates with the atmosphere through some of the slots 36 and a large air aperture 57 formed in the box bottom and adapted to be wholly or partially closed by disc 58 of substantially circular shape and including a radial ear whereby the disc is pivoted upon a screw 60 threaded into the box bottom from the lower side thereof.

The bottom of each heat chamber is covered with heat insulating material 62 having holes registering with the apertures 57 and supporting three pairs of insulators 63. In the left hand heat chamber three electrical heating elements or resistors a, b, a are each supported at their ends by a pair of electrical insulators. In the right hand heat chamber resistors c, b, c are supported in a similar manner. The resistors b extend diagonally from the left hand end of one of the resistors a or c to the right hand end of the other resistor a or c (Fig. 11).

That figure also shows electrical circuits for the motor and resistors and including terminals 65, 66 taking the usual form of prongs embedded in a holder and adapted for connection to an electric socket. These terminals are connected by conductors 67, 68 to conductors 69, 70 the other ends of which connect to the motor M. One or both of the connections between conductors 67, 69 and 68, 70 are switches (not shown) controlled by a timer T mounted on the control board 76 attached by fasteners 23 to the outer side of the lower half of the left hand transverse box board 9 (Fig. 3, 6). The timer may be set for various periods at the ends of which it opens the switch or switches.

From the conductor 70 extend shunts 71, 72, 73 each containing a manually operable switch a—a, b—b, c—c respectively. Each of these switches which control the connections between their respective shunt and conductor 70 may be manipulated by a button 75 which is also mounted on the control board 76.

Each shunt 71—73 divides into two branches 77 connected to a pair of resistors denoted by the same letter. The resistors a, b, a and c, b, c in the two heat chambers are also connected by conductors 79 to conductor 69. In the conductor 70 is a rheostat including a variable resistance 80 which may wholly or partially be made a part of the circuit by the swinging of a contact arm 82 having contact at its outer end with the resistance. In the conductor 70 is also a manually operable motor switch 84 having a button 85 mounted on the control board.

After the patient has placed himself upon the couch forming the top of the table the instrumentalities on the control board which are presumed to be in inoperative position, are manipulated according to the kind of treatment desired.

If it be assumed that the latter is to consist of the administration of vibrations, the timer is set for the period during which the vibrating treatment is to continue.

- 5 The motor switch 84 is closed with the rheostat arm 82 disposed at or near the free or dead end of the resistance 80 (Fig. 11). The switches a—a, b—b, c—c, are presumed to be open and stay open during a purely vibratory treatment. 10 By moving the contact arm 82 clockwise the speed of the motor may be increased to the desired value. The eccentric load on the motor shaft (Fig. 10) develops a dynamic load or unbalanced centrifugal force transmitted through 15 the bearing block and cap to the couch which moves up and down and during the latter movement compresses the springs 14. During the vertically reciprocating movement the slotted legs of the angles 22 slide on the pins 26. This vibratory treatment will automatically stop at the 20 end of the period for which the timer has been set.

If the patient is to receive a heat treatment only the motor switch M is opened and the timer 25 is set for the period during which the treatment is to be administered. Switches a—a, b—b, c—c, or any of them are then closed to heat the resistors and the admission of air to the heat chambers is regulated by the discs 58. Convection currents of heated air emerge through all 30 or some of the slots 36. At the end of the period for which the timer is set, the latter interrupts the circuit.

Obviously the patient may also receive vibratory and heat treatments at the same time.

Figures 12, 13 and 14 show a modified form of my invention which has parts also common to the preferred embodiment and indicated by characters of reference found in both embodiments.

40 These parts are therefore described by reference to the description of the corresponding parts of Figure 1-11.

The slots 36 are arranged transversely of the couch and are not limited to any specific number. 45 Figure 12 shows four of such slots arranged adjacent either end of the couch. The space between the two innermost slots of the two sets each numbering four, has four slots each of a length of about one-third of the length of the 50 longer slots and aligned with a slot extending from the opposite longitudinal side of the couch. The inner ends of the pair of short slots extending from one of the longitudinal sides of the couch are spaced from the inner ends of the 55 short slots extending from the opposite longitudinal side.

To the underside of the space between the inner ends of the short slots is secured by flanges extending from the upper ends of its sides and 60 fasteners 39, the bearing block 38 which carries on its lower side a cap 40. The cap and the bearing block afford a mounting for a motor M which includes a shaft 42 carrying upon one end a fan 45. The motor shaft may be eccentrically 65 loaded by means illustrated in Figure 10.

A box 37 of heat insulating material encloses the lower portion of the bearing block, the cap, motor and fan and rests with its lower wall edges upon the central part of the box bottom 10.

70 The box 8—10 has four vertical transverse partitions 55 the two innermost one of which form with the intermediate portions of the longitudinal boards 8 a chamber for the motor and fan and for a pair of resistors b. The motor and 75 fan are protected by the box 37 from the heat

generated by the resistors which extend parallel to the longitudinal boards 8 of the box. Each insulator is supported at either end by an insulator 63.

In either of the chambers bounded by one inner and one outer partition 55 is a pair of similar resistors a, a and c, c respectively, arranged in parallelism to one another and the longitudinal boards 8.

The resistors are connected to one another and a source of current in a manner similar to the arrangement of Figure 11. The motor and the resistors are further controlled by a timer and switches as shown in that Figure 11, which also shows a rheostat controlling the motor.

Figures 15 and 16 illustrate a second modification which is distinguished from the heretofore described embodiments by arranging the control means such as timer, motor and resistors, switches and rheostat in a separate control box 2 so that these control means may be manipulated from the outside of the control box. The same is supported on a table 3. A conductor cable 4 is composed of conductors still to be described and connecting the motor and resistors in the table box to the control means in the control box 2.

In the wiring diagram of Figure 16 conductors 67, 68 are adapted for connection to a source of current and are also connected to conductors 69, 70 respectively. One or both of the connections between conductors 67, 69 and 68, 70 are switches (not shown) controlled by a timer T mounted on the outer face of the front wall of the box 2. The conductor 69 is connected to one side of the motor, the other side of which is connected to one end of the conductor 70. The same is connected to shunts 71, 72, 73 each containing a manually operable resistor switch a—a, b—b, c—c, respectively. Each switch may be manipulated by a button 75 on the outer side of the front wall of the control box 2. The other end of each shunt is connected to one terminal of a pair of resistors a, a, b, b, c, c, respectively, each pair of resistors preferably administering heat to a particular part of the body. The other terminals of each pair of resistors are connected by a branch 79 to the conductor 69.

In the conductor 70 is a rheostat comprising a variable resistance 80 which may wholly or partially be made part of the motor circuit by the swinging of the contact arm 82 having contact at its outer end with the resistance.

The inner or pivot end of this arm is connected to the fixed contact of a motor switch 84 having a button 85 mounted on the front wall of the control box 2. The pivot end of the arm of switch 84 is connected to the return conductor 70.

From each conductor 71, 72, 73 extends a branch conductor 74 containing a lamp l and connected at the other end to the conductor 69.

The operation of the arrangement of Figure 16 depends on whether the treatment is to be purely vibratory or purely heat administering or a combination of both. In the case that the treatment is to be purely vibratory, only the motor switch is closed with the rheostat arm positioned upon the outer end of the resistance 82. Then the rheostat arm is moved towards the inner end of the resistance to the extent desired.

The switches a, a, b—b, c—c when closed will cause the respective pair of the resistors to administer heat to a particular part of the body.

The closed state of one of the resistor switches is indicated by the burning of the lamp l in the respective branch 74.

While the foregoing disclosure discloses the preferred embodiment of the invention in its specific details, I desire it to be understood that these details are mere examples, not limitations of the invention and that changes or modifications may be resorted to without departing from the spirit or scope of the invention as defined by the appended claims.

What I claim and desire to secure by Letters Patent of the United States is:

1. A therapeutic table for administering heat and vibration treatments comprising a box portion having side and end walls and a bottom wall, adjustable legs supporting said box portion, a patient supporting, upholstered table top mounted on said box, said table top having spaced apart, air circulating slots therein, resilient means interposed between said table top and said box, an electric motor having a dynamically unbalanced shaft secured to the under side of said table top at or adjacent the center thereof to impart mechanical vibrations thereto, transverse partitions dividing the interior of said box portion into a motor chamber and separate heat chambers, electric heating elements in each heat chamber, and an electric circuit connecting said motor and said heating elements with a source of electrical energy, said circuit including manually operated switches controlling said motor and said heating elements respectively.

2. A therapeutic table for administering heat and vibration treatments comprising a box portion having side and end walls and a bottom wall, adjustable legs supporting said box portion, a patient supporting, upholstered table top mounted on said box, said table top having spaced apart, air circulating slots therein, resilient means interposed between said table top and said box, an electric motor having a dynamically unbalanced shaft secured to the under side of said table top at or adjacent the center thereof to impart mechanical vibrations thereto, transverse partitions dividing the interior of said box portion into a motor chamber and separate heat chambers, electric heating elements in each heat chamber, an electric circuit connecting said motor and said heating elements with a source of electrical energy, said circuit including manually operated switches controlling said motor and said heating elements respectively, and a fan on said motor shaft impelling a flow of air through said motor chamber to remove excess heat therefrom.

PETER BACHIN.
